UNITED STATES PATENT OFFICE.

EDWARD KAYE, OF MONACA, PENNSYLVANIA, ASSIGNOR TO THE WELS-BACH LIGHT COMPANY, OF GLOUCESTER CITY, NEW JERSEY.

DESIGN FOR A SHADE FOR INCANDESCENT GAS-LIGHTS.

SPECIFICATION forming part of Design No. 26,003, dated September 8, 1896.

Application filed June 29, 1896. Serial No. 597,472. Term of patent 14 years.

To all whom it may concern:

Be it known that I, EDWARD KAYE, a citizen of the United States, residing at Monaca, in the county of Beaver and State of Pennsylvania, have invented and produced a new and original Design for a Shade for an Incandescent Gas-Light, of which the following, taken in connection with the accompanying drawings, is a specification.

Figure 1 is an elevational view of a shade of my design, and Fig. 2 is a sectional view of the same, and these two figures are deemed necessary for properly illustrating my design.

My design for a shade will be best understood by reference to the accompanying drawings.

The leading or essential feature of my design may be said to be a shade shaped like the middle part of an egg, as shown in the draw-

ings, and having transparent conoidal projections *a*, displayed upon a translucent ground *b*, and having at the top thereof flutes *c* and scallops *d*. As shown in the drawings, the conoidal projections are of different sizes, and are arranged more or less irregularly, as shown.

What I claim as new, and desire to secure by Letters Patent, is—

The design for a shade for an incandescent gas-light, substantially as shown and described.

In testimony whereof I have hereunto signed my name in the presence of two witnesses.

EDWARD KAYE.

Witnesses:

ERNEST J. WHISLER,
N. F. HURST.
